United States Patent

Des. 235,816
Patented July 8, 1975

235,816

HOT BEVERAGE DISPENSER

Richard B. Hall, Canton, Ohio, assignor to
Sunbeam Corporation, Chicago, Ill.

Filed June 22, 1973, Ser. No. 372,890

Term of patent 14 years

Int. Cl. D7—04; D15—08

U.S. Cl. D94—3 B

FIG. 1.

FIG. 2.

FIG. 3.

FIG. 4.

FIG. 1 is a front perspective view of a hot beverage dispenser showing my new design;

FIG. 2 is a front elevational view thereof;

FIG. 3 is a side elevational view thereof, the other side being a mirror image; and

FIG. 4 is a top plan view thereof.

The back of the hot beverage dispenser is substantially plain, except for the conventional hinge shown in FIGS. 3 and 4, and unornamented.

I claim:

The ornamental design for a hot beverage dispenser, as shown and described.
